Attest.

UNITED STATES PATENT OFFICE.

WILLIAM H. CALHOUN, OF NEW YORK, N. Y., ASSIGNOR TO FRENCH BATTERY & CARBON COMPANY, OF MADISON, WISCONSIN, A CORPORATION OF WISCONSIN.

COMBINATION ELECTRIC LANTERN AND SPOTLIGHT.

Application filed May 5, 1922, Serial No. 555,713. Renewed September 27, 1924.

To all whom it may concern:

Be it known that I, WILLIAM H. CALHOUN, a citizen of the United States, residing at New York, in the county of New York and State of New York, have invented a certain new and useful Improvement in Combination Electric Lanterns and Spotlights, of which the following is a specification.

10 Commercial flash-lamps include a case with a battery in it, a lamp at one end energized by the battery and a parabolic reflector for the lamp adapted to concentrate the rays from the lamp in a substantially parallel beam, striking a single point or object at a substantial distance—sometimes a couple of hundred feet away from the operator.

Electric lanterns for railroad and other use include a battery case supported on stands adapted to rest upon the floor or ground, there being interposed in the space below the battery a fully exposed electric light bulb energized by the battery and adapted to radiate light beams both downward and in all directions about the lantern:—a light distribution which is essential in the conditions of work for which a lantern is required. As used in the prior art, 30 these lanterns are incapable of throwing a beam of light to any substantial distance, as would at times be desirable in many lines of work where a lantern of this type might be useful.

35 The object of this invention is to provide a lantern of this type with a parabolic reflector which may be selectively placed, so that either the light rays from the electric light bulb are concentrated in a beam in one single direction, thereby rendering the lantern useful as a flash-light proper, or the light rays are allowed to scatter, as with the ordinary lantern, thereby leaving the ordinary lantern functions undisturbed.

45 The invention consists in means for attaining the foregoing objects, which can be easily and cheaply constructed, which is satisfactory in use and in not readily liable to get out of order. More particularly, the 50 invention consists in many features and details which will be hereafter more fully set forth in the specification and claims.

Referring to the drawings in which like numbers designate the same parts through- 55 out the several views:

Figure 1 is the side elevation of a lantern equipped with the mechanism of this invention, the reflector being in the position in which the light beams from the lamp can radiate freely.

60 Figure 2 is a somewhat enlarged vertical section of the device of Figure 1.

Figure 3 is a changed position view of the essential parts of Figure 2, showing the reflector in flash-light position, viz: that in which the rays from the electric lamp are directed by the reflector into a beam extending in a single direction.

Figure 1 shows an ordinary lantern case 10, supported by angularly disposed legs 12 from a conventionally open presumably circular ring 14 resting on the floor and holding the lower ends of these legs rigidly in the position predetermined by the designer of the lantern. At the top of the case 10 is 75 a conventional handle 16, adapted to be grasped by the user.

The case 10 is equipped with a conventional form of battery 18, one of whose terminals delivers current by conventional means to a contact 20, engaging the central terminal 22 of an electric light bulb 24, whose outside terminal 26 is in screw threaded engagement at 28 with a projecting case portion 30 which receives, in conventional manner not shown, electricity from the other terminal of battery 18, the result being that current from the battery 18 flows through the lamp device 24 to illuminate the filament 24^a thereof.

90 The parts thus far described are purely conventional construction and may be varied within wide limits without in any way departing from the invention.

In applying this invention to the conventional mechanism just described, a parabolic reflector 32 is produced, the same being of suitable size so that when placed in the position of Figure 2, it will in nowise interfere with the normal operation of the lamp 100 24 in connection with the electric lantern of Figure 1, and that when placed in the position shown in Figure 3, beams of light which emanate from the filament 24^a of the electric lamp 24 will all be turned downward by the inside surface of the reflector, exactly as would be the case were the reflector and lamp mounted in an ordinary flash-light—this with the result that when the operator wants to use the device of Figure 110

3 for flash-light purposes, all he has to do
is to turn the lantern device in such a di-
rection that the central axis of the lamp and
the reflector 32 will point through the ring
5 14 to the single object which he wishes to
illuminate.

Many different ways are conceivable for
detachably securing the reflector 32 so that
it is selectively mountable with reference to
10 the lamp and the rest of the lantern in the
two positions shown in Figures 2 and 3, the
particular mechanism which happens to be
used for the purpose in the drawings is
merely to provide the case portion 30
15 which surrounds the terminal parts of the
lamp 24 with an externally screw threaded
cylindrical portion 34 with which the in-
ternal screw threads 36 in a central perfora-
tion in the reflector 32 are adapted to inter-
20 fit in conventional and obvious manner as
fully illustrated in the drawings.

The particular screw thread attachment
34—36 for the reflector has an additional
25 advantage of its own of providing a simple
slow motion mechanism by which the re-
flector may be moved as carefully as desired
axially of the lamp 24 to thereby, while the
reflector is still in the position of Figure 3
30 as regards the lantern, focus the reflector
with reference to the lamp so that rays of
light from the lamp 24 will strike the re-
flector in the proper manner to be directed
as a parallel beam through the ring 14.

What I claim as new and desire to secure
35 by Letters Patent is:

1. In a mechanism of the class described,
an electric lantern mechanism with an elec-
tric light bulb protruding therefrom, adapt-
40 ed to receive current from the lantern
proper, screw threads on part of the lantern
from which the electric lamp projects, con-
centric with the axis of the lamp, and a
parabolic reflector having a central screw
45 threaded perforation therein adapted to en-
gage said screw threads on the lantern, the
whole being arranged so that the reflector
may be reversibly placed on said screw

threads to in one position act on rays of
light from said lamp to direct them into a
beam, and in the other leave the rays from
the lamp entirely unobstructed. 50

2. In an electric lantern, the combination
of a casing having an electric light bulb
protruding therefrom adapted to receive
55 current from an electric cell arranged with-
in the casing, and a dished reflector having
means for cooperation with a portion of the
casing to reversibly attach the reflector to
the casing, whereby said reflector acts in one
60 position to concentrate light rays from the
bulb into a beam and in a reversed position
to permit diffusion of said light rays.

3. An electric lantern including a casing
having an electric light bulb protruding
65 axially therefrom adapted to receive current
from an electric cell arranged within the
casing, and a dished reflector having means
centrally thereof for cooperation with a por-
tion of the casing to reversibly attach the
70 reflector to the casing axially thereof, where-
by said reflector acts in one position to con-
centrate light rays from the bulb into a
beam and in a reversed position to permit
diffusion of said light rays.

4. An electric lantern including a casing
75 having an extension thereon, an electric
light bulb protruding from said extension
adapted to receive current from an electric
cell arranged within the casing, and a dished
reflector having means for cooperation with
80 a portion of said extension to reversibly at-
tach the reflector to said extension, whereby
said reflector acts in one position to concen-
trate light rays from the bulb into a beam
85 and in a reversed position to permit diffusion
of said light rays, the extension on said cas-
ing tapering towards said bulb whereby it
is received within the dished portion of the
reflector in one of the aforesaid positions of
90 the latter.

In witness whereof, I have hereunto sub-
scribed my name.

WILLIAM H. CALHOUN.
